2 Claims. (Cl. 158—115)

1

The present invention is directed to an apparatus which is suitable for igniting combustible mixtures. More particularly, the invention is directed to an apparatus adapted for use in connection with pressure releasing systems in which large quantities of combustible fluids are suddenly released to a flare stack.

In the petroleum refining industry a number of processes operate under elevated pressure. For example, in thermal polymerization in which propylene and butylenes are subjected to high pressure and high temperatures to cause polymerization thereof, it is sometimes necessary to release the pressure suddenly and to discharge the contents of the thermal polymerization unit. When this happens, large quantities of gaseous and liquid combustible mixtures of hydrocarbons must be carried away from the unit to a safe distance and ignited. Otherwise, large quantities of hydrocarbons would be released in areas where they may be ignited to cause dangerous fires. In catalytic cracking and other cracking operations such as those of the thermal type, it is also necessary at times to provide some pressure releasing means which usually have included elongated vertical stacks located at a distance from the unit. Locating the stacks at a distance from the unit is not a very good solution to the problem since the pipeline connecting the flare stack to the unit may cause delay in igniting the released fluids and, therefore, build up in the areas immediately surrounding the unit a dangerous combustible mixture. Catalytic cracking operators usually provide, adjacent the catalytic cracking unit, elongated stacks some 200 feet in height which allow the ready release of the unit to the stack where pilot lights are available to cause immediate ignition of the released material. However, the difficulty exists of maintaining the pilot light on such flare stacks ignited. If the pilot light is maintained at the base of the flare stack, it would be possible to protect the pilot light and to keep it burning at all times to make it available for igniting the combustible mixtures. However, to maintain a pilot light at the base of the stack presents a hazardous condition especially when the flare stacks are located adjacent a catalytic cracking unit. When the pilot lights are located adjacent the upper end of the flare stacks, it is difficult to maintain them in a lighted condition in view of the winds prevailing at the elevation of 200 feet or more to which the flare stacks usually extend for safety purposes.

To emphasize the seriousness of the situation in maintaining an elevated pilot light available

2

at all times, recourse has been made to raising a burning torch on a cable, to gas fire ladders, and other elaborate sparking devices none of which has proved entirely satisfactory. Tracer bullets and flares have even been shot through the gas issuing from the top of the flare stacks to cause burning thereof.

As mentioned before, none of the devices of the prior art has been entirely satisfactory. Accordingly, it is an object of the present invention to provide an apparatus which will allow efficient and satisfactory ignition of a gaseous mixture issuing from an elongated flare stack.

Another object of the present invention is to provide an apparatus suitable for igniting a combustible mixture issuing from the top of a vertical elongated conduit.

The objects of the present invention may be achieved by providing in combination apparatus which includes an elongated conduit having located adjacent an open upper end thereof a suitable burner mechanism such as the conventional burner available on the market provided with a shield which protects the burner and also serves to define a passageway for conducting the flame. The burner should be provided, of course, with a source of a free oxygen-containing gas or air and a suitable fuel source. The elongated conduit communicates at its lower end with the system from which pressure is to be released. Such systems will include a catalytic conversion operation such as a catalytic cracking operation or other high pressure units in a petroleum refinery such as thermal polymerization or cracking units, distillation operations which are conducted under pressure, and any of the numerous processes available to the refiner from which large volumes of combustible mixtures may be released. Located adjacent the burner is an ignition system including an electrical resistance element located in the path of a mixture of a combustible fuel and a free oxygen-containing gas or air. The ignition means allows the ignition of the combustible mixture in the igniter which in turn will ignite the combustible mixture in the pilot light and also serves to keep it burning at all times. The resistance element is energized through suitable electrical conductors connecting to a source of electrical energy.

The invention may be described briefly then as involving an elongated vertical stack or conduit with its lower end in communication to the system from which pressure may be released and having an open upper end which is provided with a pilot burner adjacent the open end and a pilot

burner igniter. The pilot burner is provided with an independent source of fuel and is so designed as to allow formation with the fuel of a combustible mixture with air. The igniter is located adjacent the pilot burner and it includes a conduit whose open upper end is located adjacent the open upper end of the vertical elongated stack and adjacent to the open passageway defined by the burner. At the lower end of the ignition means a conduit is provided defining a passageway in fluid communication with a source of fuel. This conduit is surrounded by a larger conduit provided with passageways or inlets for admission of air for admixture with the fuel introduced into the ignition means. The mixture then flows across the resistance element which causes it to be ignited when the resistance element is energized.

The invention will be illustrated by reference to the drawing in which:

Fig. 1 is a front elevation of a device in accordance with the present invention including an elongated vertical conduit, a burner and an ignition means for said burner;

Fig. 2 shows a detail of the burner, the ignition means, and the arrangement of the two in combination with the elongated vertical conduit adjacent the upper end thereof;

Fig. 3 is a view looking downwardly on the device of Fig. 2; and

Fig. 4 presents a detail of the construction of the ignition means.

Referring now to the drawing, numeral 11 designates an elongated vertical conduit such as a flare stack of a catalytic cracking unit. The lower end of stack 11 is in communication by a line 12 controlled by valve 13 with the catalytic cracking unit from which pressure may be released. Arranged at the upper end of flare stack 11 is a pilot burner 14 defining a passageway whose upper end discharges adjacent the upper end of stack 11 and whose lower end is in communication by a smaller conduit 15 with a source of fuel not shown. Located adjacent the pilot burner and connected thereto by a plate 16 is an ignition means 17 defining a conduit whose upper open end discharges adjacent the pilot burner 14 and is connected thereby by plate 16. The lower end of the passageway defined by ignition means 17 connects into a smaller conduit 18 defining a passageway in communication with a source of fuel not shown which may be the same source of fuel in communication with the passageway defined by conduit 15. Connecting into the ignition means 17 at a point above the juncture therewith of conduit 18 is electrical connecting means 19 which is provided with a transformer 20 and an explosion-proof switch 21.

Referring now to Fig. 2, the burner 14 is located adjacent the top of stack 11 as shown and is provided with a conduit 15. Adjacent the burner 14 is ignition means 17 which is connected to burner 14 by plate 16 allowing the passageways defined by burner 14 and ignition means 17 to discharge at a point slightly above the open end of stack 11. Burner 14 includes a jet 22 through which the fuel admitted through conduit 15 is discharged thereto and means indicated by 23 which may be perforations in burner 14 for admission of air thereto to form a combustible mixture. Ignition means 17 includes a relatively long vertical portion whose lower end is provided with a resistance coil 24 electrically connected by conductors 19 to a source of electrical energy not shown. Conduit 18 providing a source of fuel for

ignition means 17 projects upwardly into the portion of ignition means 17 indicated by the portion 25 which is provided with perforations or inlets 26 which allow air to be admitted into the region adjacent the extension of the vertical conduit 18 which is indicated by the numeral 27.

The electrical conductors 19 lead into ignition means 17 through lead in boxes 28 provided with insulating bushings 29 which are constructed to withstand a temperature of about 2000° F. The electrical conducting means 19 connect to resistance element 24 which provides a source of heat for ignition of the combustible mixture formed, in the passageway defined by the ignition means 17, by admission of fuel from conduit 18 and air from perforations or ports 26.

When operating the improved device of the present invention, it may be assumed for purpose of illustration that the unit to which stack

11 is connected has to be released suddenly and valve 13 is opened connecting the unit being released by line 12 to stack 11 and providing a sudden source of combustible mixture. Under these conditions, to be assured that the admixture is properly ignited at the upper end 14 of stack 11, fuel should be flowed through lines 15 and 18, respectively, to the pilot burner and to the ignition means; explosion-proof switch 21 connecting the ignition means 17 to a source of electrical energy would be closed thus energizing the resistance coil 24 and causing it to be heated to a point where it will ignite the mixture of fuel gas and air passing over it. The ignited mixture issues from the upper end of the passageway defined by ignition means 17 and immediately ignites the pilot light which in turn causes ignition of the combustible fluid issuing from the top of flare stack 11.

Generally it will be desirable to maintain the pilot burner ignited at all times. It will usually be desirable to provide a continuous flow of combustible fuel gases through conduit 15. However, under conditions that it becomes apparent that the pilot light may be blown out by high winds or become extinguished for any reason, it may be desirable to energize the resistance 24 by closing the switch 21 even when large quantities of combustible fluids are not being released to the flare stack.

It will usually be desirable to provide an elongated vertical flare stack for a catalytic cracking unit about 300 feet above ground elevation. Such a stack serving a unit processing about 30,000 barrels of feed stock per day may be approximately 24 inches in diameter. The pilot burner may be constructed of 2-inch pipe and suitably may be served with a fuel line about 1 inch in diameter. It will be desirable to construct the pilot burner out of steel alloy containing approximately 18% by weight chromium and 8% nickel. Similarly, the ignition system may be constructed of a steel alloy containing 18% chromium and about 8% nickel and will include a pipe of about 2 inches in diameter and 10 feet long. This ignition means may be served by a conduit constructed of about 3/8 inch tubing connecting to a suitable fuel system.

The electrical conducting means providing electrical energy to the resistance may be constructed of suitable electrical conducting materials. It should be provided of sufficiently rugged construction to withstand temperatures of about 2000° F. An alloy of about 80% nickel and 20% chromium gives satisfactory results. Similarly, the resistance coils should be constructed to pro-

vide a satisfactory service up to about 2000° F. and may be constructed of close wound 80-20 nickel chromium alloy wound on a $\frac{1}{4}$ inch arbor for $\frac{3}{4}$ of an inch and then stretched to 1 $\frac{1}{2}$ inches. The transformer and the electrical conducting means should be provided to produce a heating current of 60 amperes through the coil at approximately 6.5 volts.

In order to illustrate the apparatus of the present invention, a small unit was constructed consisting of 2 inch pipe having a vertical length of 10 feet. A $\frac{3}{8}$ inch tube was run up the side of the 2 inch pipe at the top open end through which gas was passed. A resistance element was placed in the lower end of the 2 inch pipe and, while gas was being introduced into the 2 inch pipe, current was passed through the resistance causing ignition of the combustible mixture of gas and air introduced thereto. The flame travelled upwardly through the 2 inch pipe to the top end thereof and ignited the gas discharging through the $\frac{3}{8}$ inch tubing adjacent thereto.

The ignition element including a resistance coil of the type described in the apparatus of the present invention was subjected to 70 amperes current at 7.5 volts for a period of 5 minutes with no apparent deteriorating effects. Ordinarily, in igniting the apparatus in accordance with the present invention, it will not be necessary to cause energization of the resistance coil for more than a few minutes at a time.

While specific dimensions and constructional materials have been given in describing the improved apparatus of the present invention, it will be apparent to the skilled worker that other dimensions and other constructional materials may be employed. For example, the burner and the ignition means have been described as being constructed of chromium-nickel alloys and steel. Obviously, other constructional material capable of withstanding the conditions to which the apparatus is put may be used. Likewise, the specific dimensions of the burner mechanism and the ignition means are not critical and may be modified such as by reducing the length of either the burner conduit or the ignition conduit. For example, the ignition means has been described as having an overall length of about 10 feet. This may be reduced to 3 feet and the gas and air introduced at the bottom thereof and ignited. Once the gas mixture is ignited the current may be cut off and the gas pressure increased forcing the flame above the element and making the short unit serve as a continuous pilot light in addition to acting as the igniter. In fact, the modification in which the ignition means serves as a burner may be preferred in some instances and, under these circumstances, the burner 14 shown in the several figures of the drawing would be eliminated and the ignition means 17 would serve as both the burner and the ignition means. Thus, for example, a mixture of gas and air would be ignited in the ignition means 17, the gas being introduced through the conduit 18 and air through ports 26 forming a combustible mixture which would then be passed in contact with the resistance coil 24 which, on energization through electrical conducting means 19 and switch 21 connecting to a source of electrical energy, would cause the combustible fuel-air mixture to be ignited. The current would then be cut off by opening the switch 21 and at the same time the gas pressure would be increased forcing the flame to travel upwardly through the passageway defined by

ignition means 17 and outwardly adjacent the open end of elongated stack 11. It will thus be seen that one aspect of our invention includes in combination an elongated conduit and an ignition means which serves both as a burner and an ignition means.

In operating the modification in which the ignition means serves as a burner, the pressure in the ignition means adjacent the region where extension 27 debouches into the ignition means 17 will be practically atmospheric pressure. Gas may be supplied through the conduit 18 at a pressure anywhere slightly above atmospheric, for example, 15 pounds per square inch gauge up to about 200 pounds per square inch gauge, which is released nearly instantaneously to slightly above atmospheric pressure as it flows into the ignition means 17. The element 24 is energized as the mixture of fuel gas and air passes over it causing ignition and combustion thereof, and after ignition has taken place the pressure is increased by about 1 to 5 pounds per square inch gauge which causes the flame to travel up the passageway defined by the ignition means 17 and to cause ignition of the combustible fluid being released through stack 11. Ordinarily, the resistance element 24 will be energized for at least 25 seconds and may be energized as long as two minutes to allow the element to reach a temperature in the neighborhood of 2000° F. to cause ignition of the combustible mixture flowing past the element. The time required for the ignited mixture to reach the open end of the passageway defined by the ignition means 17 from the point of ignition will usually be one second or less.

Thus, in accordance with this mode of our invention, the ignition means serves as the burner and the combustible fuel-air mixture is ignited by energizing the resistance element 24 for a time sufficient to cause ignition and combustion of the combustible mixture. The explosion proof switch 21 is then opened cutting off the flow of current to the resistance element 24. Gas pressure is then increased slightly by about 1 to 5 pounds per square inch gauge causing the flame to travel up the passageway and ignite the combustible fluid issuing from stack 11. Numerous modifications will suggest themselves to the skilled workman.

The nature and objects of the present invention having been fully described and illustrated, what we wish to claim as new and useful and to secure by Letters Patent is:

1. A device adapted for the combustion of combustible mixtures which comprises a vertical elongated conduit defining a passageway in fluid communication at a lower end with a source of combustible fluid and open at an upper end, an elongated vertical burner attached to said elongated conduit adjacent an upper end thereof provided with an interiorly arranged vertical jet and defining a plurality of ports below the jet communicating an interior of the burner with an outer surface thereof, a conduit defining a passageway connected to and communicating said jet with a source of fuel, a vertical ignition means including a resistance element attached to said burner and to said elongated conduit and arranged adjacent said burner and said elongated conduit, said ignition means being provided with a vertical jet and defining a plurality of ports below the jet communicating an interior of the ignition means with an outer surface thereof and being provided with electrical conduction means connecting said resistance element to a source of electrical energy, said burner and said ignition means defining

open passageways adjacent the open upper end of the elongated conduit parallel to each other and to said elongated conduit, and a horizontal baffle member having a plane horizontal surface spaced above and facing the burner and the ignition means, said baffle member extending completely over the burner and ignition means and attached thereto and being spaced horizontally from the open end of said elongated conduit whereby said baffle member covers the open end of said burner and ignition means but not the open end of said elongated conduit.

2. A device adapted for the combustion of combustible mixtures which comprises, in combination, a flare stack defining a passageway in fluid communication with a source of combustible fluid at its lower end and open at its upper end, an elongated vertical burner located on said flare stack adjacent the open upper end provided with an interiorly arranged vertical jet and defining a plurality of ports below said jet communicating an interior of the burner with an outer surface thereof, a relatively small conduit defining a passageway connecting said jet to a source of fuel, said burner having an open upper end adjacent the open end of said flare stack, a vertical ignition means including a resistance element and comprising a conduit located adjacent said burner and said flare stack provided with an interiorly arranged vertical jet and defining a plurality of ports below the jet communicating an interior of the ignition means with an outer surface thereof, electrical conducting means con-
